US00D982314S

(12) United States Design Patent (10) Patent No.: US D982,314 S
(45) Date of Patent: * Apr. 4, 2023

(54) WALLET

(71) Applicant: Dango Products, LLC, Portola Valley, CA (US)

(72) Inventors: Thuan Tran, Santa Clara, CA (US); Charlie Carroll, Palo Alto, CA (US); Binh Tran, Santa Clara, CA (US)

(73) Assignee: Dango Products, LLC, Portola Valley, CA (US)

() Term: 15 Years

(21) Appl. No.: 29/815,386

(22) Filed: Nov. 12, 2021

Related U.S. Application Data

(63) Continuation-in-part of application No. 17/470,825, filed on Sep. 9, 2021, now Pat. No. 11,337,498, which is a continuation of application No. 17/227,204, filed on Apr. 9, 2021, now Pat. No. 11,178,947.
